UNITED STATES PATENT OFFICE.

HORACE B. CAMP, OF AKRON, OHIO.

LETTER FOR ELECTRIC SIGNS.

No. 836,088.

Specification of Letters Patent.

Patented Nov. 20, 1906.

Application filed July 3, 1905. Serial No. 268,277.

To all whom it may concern:

Be it known that I, HORACE B. CAMP, a citizen of the United States, residing at Akron, in the county of Summit and State of Ohio, have invented certain new and useful Improvements in Letters for Electric Signs, of which the following is a specification.

This invention relates to improvements in letters for electric signs; and the object is to provide a simple construction of letter which may readily be attached to the supporting-board or other part and in which the electrical connections and wiring are effectually insulated and protected from the weather and from contact with the supporting-board or adjacent woodwork.

With the above object in view the invention consists in the novel features of construction hereinafter fully described, particularly pointed out in the claims, and clearly illustrated in the accompanying drawings, in which—

Figure 1 is a top plan view of a letter constructed in accordance with my invention; Fig. 2, a sectional view taken on the line *a a* of Fig. 1; Fig. 3, a sectional view taken on the line *b b* of Fig. 1; Fig. 4, a plan view of under side of letter; Fig. 5, a sectional view upon the line *c c* of Fig. 4.

Referring now more particularly to the drawings, 1 designates the body portion of the letter, which consists of an integral piece of earthenware formed in any desired style. The body portion 1 is formed upon its top with a channel or recess 2 and upon its under side with a similar channel 3, said channels 2 and 3 being separated by a wall or partition 4. Formed integral with the wall 4 are a series of depending sockets 5. These sockets 5 are constructed and arranged to receive the socket end of the ordinary incandescent electric lamp, the bottom of said sockets being formed to accommodate the screws and contact-plates for conducting the electric fluid from the main-line wires through the lamps, as illustrated. The side walls 6 of the channel or recess 3 project beyond the bottom of the sockets 5, so that said sockets are disposed wholly within the recess 3. The sockets 5 are provided at their upper ends with circular beads or ridges 7, which serve to prevent any moisture which may collect in said recess 2 from running thereinto, and thus come into contact with the wiring and electrical connections of the lamp. After the

lamps have been inserted into the sockets 5 and connected with the main-line wires in the usual manner the channel or recess 3 is filled with a suitable plastic insulating composition, thus completely covering the sockets 5, 60 the wiring, and electrical connections.

In order to attach the letter to the supporting-board or other part, I provide the side walls of the channel 3 at suitable intervals with pairs of lugs 8, disposed one upon each of said walls and spaced from the wall 4. Upon the top of these lugs, between the same and the wall 4, a plate 9 is positioned, which is provided with an opening to admit the passage of a bolt, the head of said bolt 70 lying in the space between the plate and the bottom of the channel. When the channel is filled with the plastic material, as above described, the bolt is held firmly in position with its shank portion extending outwardly 75 therefrom, by means of which the letter may be readily attached to the desired part.

By forming the sockets wholly within the channel or recess 3 a flat surface is presented to the supporting-board or other part, thus 80 obviating the boring of holes to receive the socket, which has been necessary heretofore in devices of this character. Furthermore, all wiring and electrical connections are completely covered and thus protected from the 85 weather and kept out of contact with the adjacent woodwork, whereby all danger from fire in consequence of defective insulation is effectually obviated.

Having thus fully described my invention, what I claim as new, and desire to secure by Letters Patent of the United States, is—

1. A letter for signs comprising a body portion provided on its top and under sides with recesses, and depending sockets for the 95 reception of incandescent lamps formed integral therewith, and disposed within the channel on the under side thereof.

2. A letter for electric signs comprising a body portion formed with a recess therein 100 and provided with depending sockets for the reception of electric lamps, said sockets being provided at their upper end with a circular bead-ring projecting beyond the bottom wall of said recess.

3. A letter for signs comprising a body portion provided upon its top and under sides with recesses, sockets extending upon the under side of the body portion and disposed within one of said channels, and bead- 110

rings surrounding the top or open end of said sockets and extending upward from the bottom wall of the other channel.

4. A letter for electric signs comprising a body portion formed with a channel upon its under side, depending sockets carried thereby, lugs carried by the side wall of said channel disposed in pairs, a plate lying across said lugs and provided with a perforation to receive the shank portion of a bolt and a bolt passing through the perforation with its head positioned between said plate and the bottom of the channel and adapted to be held in position by means of suitable filling material.
- 15 5. A letter for electric signs comprising a body portion formed on its under side with a

recess, and depending sockets formed integral with said body portion and disposed within said channel.

6. A letter for electric signs comprising a body portion formed on its under side with a recess and depending sockets formed integral with said body portion and disposed within said channel, the outer walls of said sockets terminating short of the outer wall of the channel.

In testimony whereof I affix my signature in presence of two witnesses.

HORACE B. CAMP.
